UNITED STATES PATENT OFFICE.

ERNEST O. CARTWRIGHT, OF SPRINGFIELD, OHIO, ASSIGNEE, BY MESNE ASSIGNMENTS, TO JAMES McGUNNEGLE, OF NEW YORK, N. Y.

PRINTING-PRESS.

1,069,764.

Specification of Letters Patent. Patented Aug. 12, 1913.

Application filed August 17, 1909. Serial No. 513,252.

To all whom it may concern:

Be it known that I, ERNEST O. CARTWRIGHT, a citizen of the United States, residing at Springfield, in the county of 5 Clark and State of Ohio, have invented certain new and useful Improvements in Printing-Presses, of which the following is a specification, reference being had therein to the accompanying drawings.

10 This invention relates to printing presses, and is in the nature of an improvement upon the printing press shown and described in Patent No. 926,851 granted to me July 6, 1909. The press therein disclosed 15 comprises a normally stationary platen and a combined form-bed and inking drum movable toward and away from said platen in a plane extending at substantially right angles to the working face of said platen.

20 The object of the present invention is to provide such a press in which the inking drum will be capable of movement transversely to the line of reciprocatory movement of the combined form-bed and inking 25 drum; in which such movement will be imparted to the inking drum by the reciprocation of said combined form-bed and inking drum; which will have a revolving ductor roller to transfer the ink from the 30 ink fountain to the inking drum; in which said ductor roller will have a resilient contact both with the fountain and with the inking drum; to provide an ink fountain having a feeding roller to coöperate with 35 said revolving ductor roller and having an adjustable feed, which feed is normally closed.

40 A further object of the invention is to provide an adjustable throw-off for the platen, whereby the platen can be adjusted relatively to the form-bed to accommodate the same for use with materials of varying thicknesses; and to enable the same to be moved out of and into its operative position, 45 without affecting said adjustment; and further, to simplify and strengthen the construction of the press as a whole.

With these objects in view my invention consists in certain novel features and in 50 certain combinations and arrangements of

parts hereinafter to be described, and then more particularly pointed out in the claims.

In the accompanying drawings, Figure 1 is an elevation of one side of the machine; Fig. 2 is an elevation of the side of the machine opposite that shown in Fig. 1; Fig. 3 is a longitudinal, sectional view taken just inside the side member of the main frame on that side of the machine shown in Fig. 1; Fig. 4 is a vertical, sectional view, taken 60 transversely of the machine on the line $\alpha\alpha$ of Fig. 1; Fig. 5 is a transverse, vertical section taken on the line $\gamma\gamma$ of Fig. 3; Fig. 6 is a longitudinal, horizontal sectional view of the inking drum and form-bed and its 65 operating mechanism; Fig. 7 is a sectional, detail view taken transversely of said form-bed and inking drum; Fig. 8 is a detail view of the cam actuated mechanism for the inking drum; Fig. 9 is an end elevation of the 70 combined inking drum and form-bed showing the operating devices for the inking rollers; Fig. 10 is a side elevation of what is shown in Fig. 9; Fig. 11 is a detail view of one of the slide blocks for the inking 75 rollers; Fig. 12 is a horizontal, sectional view of the ductor roller and its operating mechanism; Fig. 13 is a detail view of the sprocket wheel for actuating the feed mechanism; Fig. 14 is a detail view of one of the 80 arms carrying the ductor roller; Fig. 15 is a transverse, sectional view of the ink fountain; Fig. 16 is a side elevation of the throw-off mechanism; Fig. 17 is a detail view of the same; Fig. 18 is a sectional, detail view of said throw-off mechanism; and Fig. 19 is a sectional, detail view of the 85 controlling device for the feed roller and the inking drum.

In these drawings I have illustrated one 90 embodiment of my invention and have shown the same as comprising a substantially horizontal main frame consisting of the side members 1 connected one to the other by the end members 2. This frame 95 may be supported at a suitable height by means of standards or legs 3. Mounted at the forward end of the main frame is a normally stationary platen 4, which is capable of movement, as hereinafter described. 100

Each of the side members 1 of the main frame is formed with an elongated opening 5, in each of which is mounted a slide block 6. Each opening 5 is preferably provided at its upper and lower edges with adjustable gibs 7 which form the slideways for the slide blocks 6.

Mounted within the main frame and carried by the slide blocks 6 is a combined form-bed and inking drum, which, in the present construction, consists of a frame or carriage 8 which carries both the form-bed and the inking drum. This frame 8 is provided at each end with trunnions 9 which extend through the slide blocks 6 and are rigidly secured thereto in such a manner as to prevent any movement of the frame or carriage 8 relatively to said slide blocks. A shaft 10 extends longitudinally of the frame 8, through the trunnions 9 and projects a short distance beyond the trunnions at each side of the main frame. The shaft 10 has connected thereto on each side of the main frame a pitman 11, each of said pitmen being connected at its opposite end to a wrist pin 12 carried by a gear 13. The gears 13 are mounted on the outer ends of a shaft 14 which is journaled in bearings 15 mounted in the side members 1 of the main frame 30 and projects a short distance beyond the outer sides of said main frame to receive said gears. A second shaft 16 is mounted in bearings 17 arranged in the side members 1 of the main frame and provided with pinions 18 which are rigidly secured thereto and which mesh with the gears 13. The shaft 16 extends some distance beyond the pinion 18 at one side of the main frame and has mounted thereon a drive wheel 19 which is connected to any suitable source of power. In the present instance I have shown the drive wheel as a belt wheel which is driven by means of the belt 20 from a motor 21 which is mounted on the main frame. 45 The form-bed may be secured to the frame 8 in any suitable manner, but, in the present instance, I have formed the carriage or frame 8 and the form-bed in a single piece, this being accomplished by providing the frame or carriage 8 with a flat front face, as shown at 22, which is arranged parallel with the platen.

The inking drum is formed separately from the carriage or frame 8 and is so mounted thereon as to be capable of a vibratory or reciprocating movement transversely to the direction of the reciprocatory movement of the frame 8. The inking drum or distributing plate may be of any suitable construction and a vibratory movement may be imparted thereto in any suitable manner, but I find the construction herein shown a very satisfactory one. In this construction the inking drum, which is shown at 23, is substantially semicircular in cross section

and is provided at its edges with inwardly extending flanges or guides 24 which are slidably mounted in guideways 25 formed in the upper and lower faces, respectively, of the carriage or frame 8. The inking drum is somewhat shorter than is the frame or carriage 8 and is, therefore, capable of a sliding movement relatively to that frame or carriage. This vibratory or reciprocating movement may be secured in any suitable manner, but I prefer to secure this movement from the reciprocation of the combined form-bed and inking-drum. To this end I have provided one end of the frame 8 and the slide block 6, which supports that end of the frame, with aligned openings in which is slidably mounted an actuating bar 26 having its inner end rigidly secured to an arm or bracket 27, which, in turn, is rigidly secured to the vibratory inking drum. The opposite end of the actuating bar 26 extends beyond the slide block 6 and has rigidly secured thereto a collar 28 having a depending projection 29 on which is mounted a roller 30. The roller 30 fits within a cam slot 31 formed in the upper portion of a block or plate 32, which is rigidly secured to the main frame, preferably by casting the same integral with the lower gib 7. This cam slot has a double curve and as the frame 8 reciprocates within the main frame, the projection 29 traveling in the cam slot 31 will impart two complete vibrations to the vibratory drum for each movement of the frame 8. Obviously, however, the construction and arrangement of this operating means may be varied and the number of vibrations, which are imparted to the inking drum during each reciprocation of the frame 8, may be varied to meet existing conditions.

The arrangement of the inking rollers and the manner of actuating the same is substantially the same as that shown and described in the above mentioned patent, and consists of a plurality of rollers so mounted as to revolve about the inking drum and across the face of the form carried by the form-bed. To this end the frame or carriage 8 is of a length slightly less than the distance between the inner sides of the two slide blocks 6 and is provided between each end thereof and the adjacent slide block with a trunnion or annular bearing surface 33, which is preferably formed integral with the frame. Rotatably mounted on the trunnion or bearing surface 33 is a plate 34 having a bearing 35 which extends about the trunnion 33 and which has rigidly secured thereto, near the outer edge thereof, a sprocket wheel 36. There is a plate 34 at each end of the frame 125 or carriage 8 and each plate has a plurality of slots or guideways 37 which are arranged substantially radially and in each of which is mounted an elongated slide block 39 having grooves in its opposite sides to engage 130

the walls of the slot and guide the slide block therein. A bearing aperture 40 is formed in the inner side of the slide block near the lower end thereof and is adapted to receive and support one end of the shaft 41 of one of the inking rollers 42, of which there are several. The opposite or outer end of each slide block 39 has a projection or pin 43 extending laterally therefrom on the side 10 opposite the inking roller. A coiled spring 45 has one end connected to the pin or projection 43 and its opposite end connected to a pin or projection 38 carried by the plate 34. The arrangement of the spring 45 is 15 such that it tends to move the slide block and, consequently, the end of the roller shaft 41, which is mounted therein, inwardly, *i.e.*, toward the inking drum and form-bed. It will be apparent, therefore, that as the plates 20 34 revolve and carry the inking rollers about the combined form-bed and inking drum, the rollers will accommodate themselves to the surface of the form-bed or drum and will receive the ink from the inking drum and distribute the same evenly over the 25 form-bed. The inward movement of the inking rollers is limited and controlled by rollers or casters 46 which are mounted upon each end of the shaft 41 of each inking 30 roller 42 and which travel upon suitable tracks extending about the frame or carriage. These tracks are preferably formed by annular members or plates 47 which are secured to the ends of the frame or carriage 35 8 and have their edges arranged substantially parallel with the inking drum and form-bed and spaced such a distance therefrom as to support the inking rollers in proper engagement with the inking drum 40 and form-bed. Movement is imparted to the plates 34, which carry the inking rollers, by means of sprocket chains 48 extending about the sprockets 36 which are secured to the bearings 35 of said plates and about other 45 sprockets 49 which are eccentrically mounted on the shaft 14 which carries the driving gears 13. The eccentricity of the sprockets 49 is such as to maintain the sprocket chains 48 at a proper tension at 50 all times during the reciprocation of the frame 8. If desired, the plates 34 may be connected by transverse rods 49^a to maintain the same in fixed relation one to the other.

A suitable ink fountain is mounted in the 55 rear portion of the main frame and preferably consists of two end members or plates 50 which are mounted upon a rod 51 which extends through the lower portions of the end plates and is supported at its opposite 60 ends in the side members 1 of the main frame. The forward portions of the plates 50 are supported on a shaft 52 which is journaled in bearings 53 formed in the side members 1 of the main frame. Mounted be- 65 tween the end members or plates 50 is a

frame comprising vertical members 54 and 55. Supported above the frame comprising the members 54 and 55 is a forwardly inclined plate 56 which forms the bottom of the ink receptacle and has its lower edge 70 bearing normally against a feed roller 57 which is carried by the shaft 52. In order to maintain the plate normally in engagement with this roller the plate is formed of resilient material and is so arranged that the 75 lower edge thereof, when free, will move into engagement with the roller and thereby cut off the supply of ink.

Means are provided for moving the lower edge of the plate 56 away from the roller 80 57 a distance sufficient to feed the desired amount of ink, and, to this end, the forward edge of the plate 56 is provided with a depending flange 58 having a series of openings therein adapted to receive the forward 85 ends of a series of rods 59 which extend through openings near the upper edges of the upright plate 54 and through slots 60 in the upright plate 55, the rear end of each of the rods or bolts 59 being provided on 90 the inside of the plate 55 with a fixed washer 61 and on the outside of said plate 55 with a thumb screw 62. Thus, it will be seen that the rods 59 fulcrum on the plate 54 and that the adjustment of the rear ends of said rods 95 in the slots 60 will cause the forward ends of the rods to move the lower edge of the plate 56, forming the bottom of the fountain or ink receptacle, toward or away from the roller 57, thereby not only enabling the 100 amount of ink fed to the forms to be regulated, but also enabling different amounts of ink to be fed to different portions of the forms. It will also be observed that should the thumb screws, or other fastening means, 105 for the rods 59 become loosened by the jar of the machine, the lower edge of the plate 56 will move into engagement with the feed roller 57 and thus automatically cut off the flow of ink and prevent the flooding of the 110 forms.

The feeding of the ink from the fountain is controlled by the rotation of the roller 57 and means are provided for interrupting the rotation of this roller without stopping the 115 machine, and, to this end, I have mounted in one of the side members 1 of the main frame a screw-threaded plug 63 which is provided on its outer end with a milled nut 64 and has its inner end extending beyond the inner 120 side of the frame member and provided with a bearing lug or trunnion 65 adapted to enter a recess 66 formed in the adjacent end of the shaft 52. In the opposite frame member 1 of the main frame there is journaled 125 a short shaft 67 which extends beyond the opposite sides of the frame member, is provided on its inner end with an enlarged head to hold the same against longitudinal movement and is detachably connected to the 130

shaft 52 of the feed roller 57. The outer end of the short shaft 67 has rigidly secured thereto a disk or plate 68 in which is slidably mounted a pin 69. A sprocket wheel 70 is 5 rotatably mounted on the shaft 67 between the disk 68 and the main frame. This sprocket wheel has rigidly secured thereto a pin 71. The pin 69 is slidably mounted in the plate 68 and when its inner end is moved beyond 10 that plate it will lie in the path of the pin 71 carried by the rotatably mounted sprocket 70. This sprocket is actuated by the sprocket chain which actuates the ductor roller and rotates continuously. Therefore, 15 the rotation of the feed roller may be controlled by moving the pin 69 into and out of the path of the pin 71 carried by the sprocket wheel 70. Suitable means are provided for so actuating the pin 69. This 20 means, in the present instance, consists of a lever 72 having one end pivotally connected to the plate 68 near the outer edge thereof, as shown at 73, and its inner end located substantially centrally of the shaft 52 of the 25 feed roller and provided with a suitable handle 74. The lever 72 has formed therein, between its opposite ends, a slot 75 adapted to receive a pin or projection 76 secured to the outer end of the pin 69, whereby the 30 movement of the lever 72 about its pivotal center will move the pin 69 into or out of the path of the pin 71. The pin 69 is preferably provided with two or more notches 77 adapted to be engaged by a pawl 78, carried 35 by the plate 68, to hold the pin in its adjusted position until the lever 72 has been actuated. Thus, it will be observed that the means for connecting and disconnecting the feed roller from the driving mechanism can 40 be readily operated from the outside of the machine and that, by arranging the handle in the axis of rotation of the shaft carrying the feed roller, this handle will remain substantially stationary, and inasmuch as the 45 outer portion of the lever carrying the handle lies close to the plate 68, this operating mechanism presents but a small amount of projecting surface which might be dangerous to the operator when the machine is being driven at a high rate of speed. 50

A suitable ductor roller is provided for transferring the ink from the fountain to the inking drum, and, in order to secure the most satisfactory results, I prefer to 55 employ a revolving ductor roller. To this end a shaft 80 is journaled in the side members 1 of the main frame at a point substantially midway between the feed roller 57 of the fountain and the inking drum 23. 60 Rigidly secured to the shaft 80 are two arms 81 which carry a ductor roller 82, which is rotatably supported at the outer ends thereof. It is desirable that the support for the ductor roller should be resilient in order that 65 a yielding pressure may be exerted upon

the feed roller and the inking drum and also that it should be adjustable to permit the adjustment of the ductor roller relatively to its coöperating parts. To this end each of the supporting arms 81 is provided at its forward end with a bearing 83 and has arranged between the bearing 83 and the shaft 80 a laterally extending web 84 which terminates short of the bearing 83. A lever 85 is pivotally mounted on the bearing 83 and has a depending portion 86 in which is journaled the adjacent end of the shaft 87 of the ductor roller 82. The body portion of the lever 85 extends above and substantially parallel with the web 84 of the 70 arm 81 and is movable toward and away from the same as the lever moves about its pivotal connection to the forward end of the arm 81, thereby moving the ductor roller 82 toward or away from the shaft 80. A bolt 88 extends loosely through that end of the lever 85 lying adjacent to the shaft 80 and also extends loosely through the web 84 of the arm 81 and for some distance beyond the same. A spring 89 is coiled about 75 that portion of the bolt 88 which lies beyond the web 84 and is confined between the web and a nut 90 screw-threaded on the end of the bolt. The tension of this spring tends normally to draw the end of the lever 85 toward the web 84 and thereby move the ductor roller 82 away from the shaft. This inward movement of the lever 85 is limited, however, by means of a set screw 91 which is screw-threaded into the web 84 and is 80 locked in position thereto by means of a jam nut 92. By means of the resilient support for the roller 82 a longer "wipe" or contact is secured with both the feed roller 57 and the inking drum, thus spreading the 85 ink over a larger portion of the ductor roller as it receives the same from the feed roller and then spreading the same over a still larger surface of the inking drum, and, by means of the set screw 91, the amount of 90 pressure exerted upon the roller, and, consequently, the length of the contact, may be adjusted. The resilient support for the ductor roller 82 also serves to absorb the shock 95 incident to the contact between the ductor roller and its coöperating parts when the machine is being operated at a high rate of speed. It will also be observed that by employing a rotary feed roller in connection 100 with the revolving ductor roller the period of contact of the ductor roller and feeding roller is materially lengthened and the friction between these parts eliminated, thereby producing an easily operated device having 105 a high degree of efficiency. 110

Movement may be imparted to the shafts 52 and 80 in any suitable manner, but I prefer to provide each of these shafts at one end with a sprocket wheel, 70 and 94, respectively, about which extends a sprocket 120

chain 95 which also extends about a sprocket wheel 96 mounted on the shaft 14 between the frame member 1 and the gear 13. While the sprocket wheels may be mounted on either end of the shafts I prefer to mount the same on that end adjacent to the driving wheel 19, as, in this manner, the driving mechanism is arranged on one side of the machine and the opposite or outer side of the machine is kept comparatively free from moving parts.

In the operation of the machine it will be apparent that the ink is carried from the fountain on the surface of the feed roller 57; that this roller is engaged by the doctor roller 82 which removes a portion of the ink from the face of the feed roller and transfers the same to the surface of the inking drum; that, as the inking rollers pass over the inking drum, they remove a portion of the ink therefrom and distribute the same over the face of the form carried by the form-bed; and that the vibratory movement of the inking drum, while the inking rollers are in contact therewith, serves to distribute the ink evenly over the length and circumference of the inking rollers and thereby cause the same to be applied evenly to the form.

As above stated, the normally stationary platen 4 is mounted on the forward portion of the machine with its working face arranged at substantially right angles to the line of movement of the combined form-bed and inking drum. This platen is designed for use with a machine operating either as a hand fed press or an automatically fed press, and, to this end, the platen 4 is loosely mounted on a shaft 193 supported in the opposite side members 1 of the main frame and is provided with means for automatically moving the same about its pivotal center on said shaft, when it is desired to use the press as a hand fed press. To this end I mount on one side of the platen a guide 194 and mount a similar guide 195 on the corresponding side of the frame at a point near and preferably directly beneath the guide 194. An arm 196 is detachably secured to the slide block 6 adjacent to the guides 194 and 195; this arm being attached, in the present instance, by means of a removable bolt 197 which forms a pivotal support for the adjacent end of the arm. The arm 196 extends between the guides 194 and 195 and has its upper and lower edges diverging toward that end of the arm opposite the point of connection to the slide block. Thus, it will be apparent that when the arm 196 is connected to the slide block and the slide block moved away from the platen, the diverging edges of the arm 196 will force the guides 194 and 195 apart, and, inasmuch as the guide 195 is fixed on the main frame, the guide 194 and the platen, to which it is se-

cured, will be moved upwardly and the platen raised to a position in which the paper can be readily fed thereto. As the guide blocks move toward the platen the diverging or wedge-shaped end of the arm 196 is moved from between the guides and the platen permitted to resume its normal position. Suitable adjustable stops 98 are provided to limit the downward movement of the platen and to maintain the same in true parallelism with the form-bed. When it is desired to operate the press as an automatically fed press the arms 196 are detached from the slide blocks 6 and the paper carried from a web 99, supported beneath the main frame, over the face of the platen and through the automatic feeding mechanism 100 which is supported upon a frame 101 movably mounted upon the forward portion of the main frame and adapted to be moved toward the rear of the press when it is desired to operate the press as a hand fed press. This automatic feeding mechanism forms no part of the present invention and is, therefore, not shown or described in detail. The driving mechanism for the automatic feed is here shown as a sprocket chain 102 extending about a sprocket 103 mounted on the outer end of the shaft 80. In order that the operation of the feed mechanism may be stopped and started as desired, a suitable clutch mechanism is provided, and, to this end, the sprocket wheel 103 is loosely mounted upon a bearing block 104 which is rigidly secured to the outer end of the shaft 80 and has slidably mounted therein a pin 105. The end of the shaft is also provided with a longitudinal socket or recess 106, in which is slidably mounted a rod 107 having at its outer end a handle 108. This rod is provided near its inner end with a recess 109. When the rod 107 is in its innermost position the pin 105 will be in its outermost position and will engage a notch 110 in the sprocket wheel 103. When the rod 107 is moved to its outermost position the pin 105 will drop into the recess 109 and the outer end of said pin will be moved out of the notch 110, thereby leaving the bearing 104 free to rotate independently of the sprocket 103.

It is desirable that means should be provided to permit of the platen being moved beyond the forward limit of movement of the form-bed, whereby the printing may be interrupted without interrupting the operation of the press; and also that means should be provided whereby the platen may be adjusted relatively to the form-bed to adapt the same for use with materials of various thicknesses, and that this adjustment should be of such a character that it will not be affected by the throwing off of the platen, but that, when the platen is returned to its operative position it will occupy a prede-

terminated position relatively to the form. To accomplish this end I provide an eccentric bearing for the shaft 193, upon which the platen is loosely mounted, preferably by means of a forwardly extending portion having a bearing sleeve 111 which is journaled on the shaft 193, thereby enabling the platen to be moved into and out of its position in alinement with the form-bed without moving the shaft relatively to its bearings. In order that the shaft 193 may be caused to move in alinement with or parallel to the plane in which the form-bed moves, I have provided the side members 15 of the main frame each with an opening 112, within each of which openings are mounted two boxes or bearing blocks 113 and 114. The innermost bearing block or box 113 is mounted on the shaft 193 and is held against vertical movement, but is capable of a certain amount of movement longitudinally of the frame. This box is provided with an inwardly extending boss 115, upon which is mounted a plate 116, the face of which is flush with the end of the boss 115, and which is held in position by the sleeve 111 of the platen. This plate serves to retain the box 113 in position and to close the opening beyond the edges of said box. The second box 114 is mounted in the main frame in front of the box 113 and is held against longitudinal movement, but is capable of a certain amount of vertical movement. The box 114 is provided with an aperture adapted to receive a collar or bearing ring 117 which is fixed therein. This bearing ring is provided with a bearing aperture adapted to receive a second bearing ring 118 which has an eccentrically arranged aperture adapted to receive the shaft 193, which is rigidly secured to the bearing ring 118 by means of a key 119, whereby the shaft and the eccentric bearing ring are caused to rotate in unison. The opening in the outer bearing ring 117 is slightly eccentric and this ring is provided on its edge, for a portion of its circumference, with teeth 120. The outer bearing ring 117 is adjusted, when the press is set up, to bring the platen into the desired position and it is then locked in that position by means of a pin or key 121 which engages between two of the teeth 120 and a recess in the bearing block 114. One end of the shaft 193 extends slightly beyond the bearing block 114 and has mounted thereon a plate 122 corresponding to the plate 116 on the opposite side of the frame member. This plate is held against rotation with the shaft by means of a projection, such as a bolt head 123 carried by the main frame and adapted to enter a horizontal slot 124 formed in the inner face of the plate 122, thus permitting the plate to fit snugly against the frame member 1 and prevent any lateral movement on the

part of the bearing boxes and eccentric rings, but holding the plate against rotary movement. The slot 124 is of sufficient length, however, to permit of a certain amount of movement of the plate 122 relatively to the projection or bolt head 123, thereby enabling the plate to travel back and forth with the shaft 193. A second plate 125, of less diameter than the plate 122, is provided with an inwardly extending projection 126 adapted to enter a transverse recess or slot 127 in the end of the shaft 193 and thereby secure the plate 125 to the shaft 193 in such a manner that the shaft is caused to rotate with said plate. A third plate or member 128 is mounted on the outer face of the plate 125 and preferably has its central portion dished or cut away so as to form a clamping ring which extends about the outer portion of the intermediate plate 125. This outer plate is firmly clamped against the intermediate plate by means of a screw 129 which extends through the two plates into a screw-threaded opening in the end of the shaft 193. The intermediate plate is provided with a handle 130, by means of which it can be rotated, thereby rotating the shaft 193 and the eccentric bearing ring 118 and moving the shaft and the platen carried thereby either forward or rearward according to the direction of movement of the handle 130. When the platen has been adjusted to the desired position relatively to the form-bed the bolt 129 is tightened down, thereby clamping the plate 128 tightly upon the plate 125 and preventing any movement of said plates relatively one to the other. The outer plate 128 has a forwardly extending portion which terminates some distance beyond the edge of the intermediate plate 125. A latch 131 is pivotally mounted between its ends on the projecting portion of the plate 128 and preferably near the lower edge thereof. This latch is provided near its upper end with a projection or lug 132 adapted to enter a recess 133 formed in the periphery of the plate 122. The plate 128 is also provided with a depending arm 134 and a spring 135 is compressed between the arm 134 and the lower end of the latch 131 and tends to hold the stop 132 in the recess 133. A second lever, or operating handle, 136 is pivotally mounted at its lower end upon the projecting portion of the plate 128. This handle is preferably located between the latch 131 and the plate 128 and is mounted to move about the same pivotal center with the latch 131, as shown at 137. The handle 136 is provided near the upper end of the latch 131 with a projection or lug 138 adapted to engage the upper portion of the latch when the handle is moved forwardly about its pivotal center. The movement of the handle about its pivotal center is limited by 130

two stops 139 and 140 arranged on opposite sides of the handle. With the parts in their normal position and the platen in its operative position, the handle 136 will lie against the stop 140 and the lug or projection 132 of the latch 131 will lie within the notch 133 of the plate 122, and, inasmuch as this plate is held against rotation, the plate 128, and, consequently, the shaft and other parts connected thereto, will be held against rotation and the platen will be held against all movement toward or away from the form-bed. When it is desired to throw off the platen the handle is moved forwardly. The first portion of the movement of the handle moves the latch about its pivotal center a distance sufficient to withdraw the stop 132 from the recess 133, thereby releasing the plate 128 from the plate 122 and enabling the same to be rotated. The further movement of the handle 136 brings the same into engagement with the stop 139 on the plate 128 and causes that plate to be rotated, thereby rotating the shaft and its eccentric bearing a distance sufficient to move the platen beyond the forward limit of movement of the form-bed. When it is desired to again resume the printing the handle is moved rearwardly and brought into engagement with the stop 140, thereby causing the plate 128 to be moved in the opposite direction. When the platen reaches its normal position the stop 132 will automatically enter the recess 133 and lock the plate 128 against further movement.

It will be apparent that the operation of the throw-off will not in any way affect the adjustment of the platen relatively to the form-bed and that, after the throw-off has been operated to move the platen out of and then into its operative position, it will occupy exactly the same position relatively to the form-bed that it did before the throw-off was operated. It will further be apparent that by mounting the platen loosely upon the shaft 193 the movement of the platen about its pivotal center to bring the same into and out of alinement with the form-bed when the press is being operated as a hand fed press will not in any way affect the eccentric bearings, inasmuch as the shaft remains stationary. Consequently, the adjustment of the bearings and the platen will not be interfered with.

The operation of the press will be readily understood from the foregoing description and it will be apparent that I have provided a press comprising a normally stationary platen and a combined form-bed and inking drum reciprocating in a plane extending at substantially right angles to the platen and having the inking drum movably mounted, whereby a vibratory movement may be imparted thereto. This vibratory movement enables the ink to be

distributed uniformly over the face of the inking drum and on the inking rollers without the necessity of vibrating the inking rollers, and, consequently, it is not necessary to provide space in which to move the plates or carriers for these rollers and it is possible to mount the frame which carries the form-bed and inking drum close to the side members of the main frame and to their supporting trunnions, and, in this manner, materially lessening the probability of the parts springing or being forced out of adjustment under heavy strains. It will further be apparent that the construction is a very economic one, has a high degree of efficiency and is little liable to accident to the inking rollers. It will also be apparent that I have provided means whereby vibratory movement is imparted to the inking drum by the reciprocation of the frame which carries the same. Further, I have provided a revolving ductor roller which is rotatably mounted in resilient arms and by this means I largely eliminate the noise and shock incident to the operation of the ductor roller, and also am enabled to secure a longer contact between the ductor roller and the inking drum and between the ductor roller and the feed roller of the ink fountain, and I have also made this contact adjustable so that the desired amount of pressure may be exerted on the ductor roller while the same is in contact with its coöperating parts. I have also provided an adjustable, normally closed ink fountain having a continuously moving feed roller at its forward end which coöperates with the revolving ductor roller to transfer the ink to the inking drum. By the constant rotation of the feed roller the ink supply is maintained always in contact with the feed roller and does not require stirring, as is necessary with the intermittent feeding devices, and, by so constraining the fountain that it is normally closed, I prevent any possibility of flooding the form should the adjusting devices for the fountain be loosened. Further, I have provided means for adjusting the platen relatively to the form-bed to accommodate the same to materials of varying thicknesses and have so arranged the throw-off mechanism that the same can be operated without affecting this adjustment and have so mounted the platen upon the supporting shaft that the movement of the platen into and out of alinement with the form-bed will not affect the adjustment of the bearings for the shaft. And further, I have so constructed and arranged the several parts of the press as to simplify and strengthen the same as a whole and increase its efficiency.

I wish it to be understood that I do not desire to be limited to the details of construction shown and described, for obvious

modifications will occur to a person skilled in the art.

Having thus fully described my invention, what I claim as new and desire to secure by Letters Patent, is:—

1. In a printing press, the combination, with a platen, a form-bed reciprocable in substantially a right line toward and away from said platen, and an inking drum connected to and movable with said form-bed and also movable relatively thereto, of means for imparting a vibratory movement to said inking drum simultaneously with each movement of said form-bed toward or away from said platen.

2. In a printing press, the combination, with a platen, a form-bed movable toward and away from said platen, and an inking drum connected to and movable with said form-bed, of means actuated by each movement of said form-bed and said inking drum either toward or away from said platen for imparting a vibratory movement to said inking drum simultaneously with such movement.

3. In a printing press, the combination, with a platen, a form-bed movable toward and away from said platen, and an inking drum connected to and movable with said form-bed and also movable relatively to said form-bed, of a fixed cam, and a connection between said cam and said inking drum, whereby the movement of said inking drum with said form-bed will impart movement to said inking drum relatively to said form-bed.

4. In a printing press, the combination, with a main frame, a platen mounted therein, a carriage mounted on said main frame and carrying a form-bed movable in a right line toward and away from said platen, and an inking drum mounted on and movable with said carriage and also movable relatively thereto, of means for imparting a vibratory movement to said inking drum simultaneously with each movement of said carriage toward or away from said platen.

5. In a printing press, the combination, with a main frame, a platen mounted on said main frame, a carriage mounted on said main frame, movable toward and away from said platen and carrying a form-bed, and an inking drum mounted on and movable with said carriage and also movable relatively thereto, of a fixed cam mounted on said main frame, and a connection between said cam and said inking drum, whereby the movement of said inking drum with said carriage will impart movement to said inking drum relatively to said carriage.

6. In a printing press, the combination, with a main frame, and a platen mounted therein, of a carriage slidably mounted in said main frame, a form-bed carried by said

carriage, an inking drum movably mounted on said carriage, a fixed cam plate carried by said main frame, and an actuating member secured to said inking drum and operatively connected to said cam plate.

7. In a printing press, the combination, with a main frame, a platen mounted in said main frame, and slide blocks mounted in said main frame, of a carriage mounted on said slide blocks, a form-bed mounted on said carriage, an inking drum movably mounted on said carriage, a plate secured to one side of said main frame and having a cam groove therein, an actuating rod secured to said inking drum and extending through one of said slide blocks, and a part carried by said actuating rod and adapted to enter said cam groove.

8. In a printing press, the combination, with a main frame, a platen mounted in said frame, a form-bed mounted in said frame and reciprocable in substantially a right line toward and away from said platen, an inking drum connected to and movable with said form-bed, inking rollers arranged to revolve about said inking drum and said form-bed, and means to continuously revolve said rollers, of means to move said inking drum transversely to the line of movement of said form-bed.

9. In a printing press, the combination, with a main frame comprising side members, a platen mounted in said main frame, a form-bed mounted in said main frame and movable toward and away from said platen, an inking drum connected to and movable with said form-bed, and inking rollers arranged to revolve about said inking drum and said form-bed, of means carried by one of the side members of said main frame and operatively connected to said inking drum for moving said inking drum transversely to the direction of movement of said form-bed.

10. In a printing press, the combination, with a frame, eccentric rings rotatably mounted on the opposite sides of said frame, a shaft mounted in said eccentric rings, a platen mounted on said shaft, and a form-bed, of means for actuating said eccentric rings to adjust said platen relatively to said form-bed, means for locking said actuating means against movement, and other means for actuating said eccentric rings to move said platen into and out of its operative position without affecting said adjustment.

11. In a printing press, the combination, with a frame, eccentric rings rotatably mounted on the opposite sides of said frame, a shaft mounted in said eccentric rings, a platen mounted on said shaft, and a form-bed adapted to move in a plane extending at a right angle to the face of said platen, of means for actuating said eccentric rings

to adjust said platen relatively to said form-bed, means for locking said actuating means against movement, and other means for actuating said eccentric rings to move said platen into and out of its operative position without affecting said adjustment.

12. In a printing press, the combination, with a main frame, eccentric rings rotatably supported by said frame, a shaft mounted in 10 and rotatable with said eccentric rings, a platen loosely mounted on said shaft, and a form-bed movable toward and away from said platen, of means for rotating said eccentric rings and said shaft to adjust said shaft and said platen relatively to said form-bed, means for locking said parts in their adjusted positions, and means for moving said platen about said shaft.

13. In a printing press, the combination, 20 with a main frame, eccentric rings journaled in the opposite sides thereof, a shaft mounted in said eccentric rings and rigidly secured thereto, a platen journaled on said shaft, and a form-bed movable toward and 25 away from said platen, of a member rigidly secured to said shaft and adapted to rotate said shaft and said eccentric rings to adjust said platen relatively to said form-bed, a second member, means for rigidly securing 30 said second member to the first-mentioned member after said first-mentioned member has been adjusted, and means for actuating said second member to rotate said shaft and said eccentric rings to move said platen into 35 and out of its operative position.

14. In a printing press, the combination, with a main frame, eccentric rings journaled in the opposite sides thereof, a shaft mounted in said eccentric rings and rigidly secured thereto, a platen journaled on said shaft, and a form-bed movable toward and away from said platen, of a plate rigidly secured to the end of said shaft and adapted to be rotated to rotate said shaft and said 45 eccentric rings, a second plate supported adjacent to said first-mentioned plate, means for rigidly securing said plates one to the other, means for moving said second plate to actuate said shaft and said eccentric 50 rings, thereby moving said platen into and out of its operative position, and positive means for limiting the movement of said second plate.

15. In a printing press, the combination, 55 with a main frame, eccentric rings journaled in the opposite sides thereof, a shaft mounted in said eccentric rings and rigidly secured thereto, a platen journaled on said shaft, and a form-bed movable toward and away from said platen, of means for actuating said shaft and said eccentric rings to adjust said platen relatively to said form-bed, a plate connected to one end of said shaft, a 60 latch carried by said plate, a part carried by

the main frame and adapted to be engaged by said latch to lock said plate in a predetermined position, and a handle pivotally mounted on said plate and adapted to actuate said latch to release the plate, whereby said plate may be rotated and said shaft and said eccentric rings actuated to move said platen into an inoperative position.

16. In a printing press, the combination, with a main frame, eccentric rings journaled in the opposite sides thereof, a shaft mounted in said eccentric rings and rigidly secured thereto, a platen journaled on said shaft, and a form-bed movable toward and away from said platen, of means for actuating said shaft and said eccentric rings to 75 adjust said platen relatively to said form-bed, a plate rigidly connected with said shaft, a part carried by said frame and having a notch therein, a spring-pressed latch pivotally mounted on said plate and having 80 a projection adapted to enter said notch, a lever pivotally mounted on said plate, a projection carried by said lever and adapted to engage said latch to release the same from the main frame, and a part carried by said 85 plate adapted to be engaged by said lever, whereby the further movement of said lever will rotate said plate.

17. In a printing press, the combination, 95 with a main frame, eccentric rings journaled in the opposite sides thereof, a shaft mounted in said eccentric rings and rigidly secured thereto, a platen journaled on said shaft, and a form-bed movable toward and away from said platen, of a plate mounted on the 100 outer end of said shaft, held against rotation but free to move longitudinally of said frame and having a notch in the edge thereof, a disk lying beyond said plate and rigidly secured to the outer end of said 105 shaft, means for rotating said disk and said shaft to adjust said platen relatively to said form-bed, a second plate supported beyond said disk, means for rigidly connecting said plate and said disk one to the other, a 110 spring-pressed latch pivotally mounted on said second plate and having a projection adapted to engage the notch in the first-mentioned plate, a lever pivotally mounted on said second plate and having a stop arranged to engage the end of said latch, 115 stops arranged on the opposite sides of said lever for limiting the movement thereof, whereby the movement of said lever in one direction will release said latch from the 120 first-mentioned plate and the further movement of said lever will rotate said plate, thereby actuating said shaft and said eccentric rings to move the platen into and out of its operative position.

18. In a bed and platen printing press, 125 the combination, with a frame, a platen and a form-bed both mounted in said frame, one

of said parts being normally fixed against movement and the other of said parts being slidably mounted in the frame to move toward and away from said fixed part, of 5 an inking drum movable transversely to the line of movement of said movable part, and means actuated by the movement of said movable part toward or away from said

fixed part for imparting a complete reciprocation to said inking drum.

In testimony whereof, I affix my signature in presence of two witnesses.

ERNEST O. CARTWRIGHT.
